UNITED STATES PATENT OFFICE.

MACE LAWRENCE MASTERS, OF MOUNT ULLA, NORTH CAROLINA.

SAFETY RAZOR.

Application filed December 13, 1921. Serial No. 522,110.

To all whom it may concern:

Be it known that I, MACE L. MASTERS, a citizen of the United States, and a resident of Mount Ulla, in the county of Rowan and 5 State of North Carolina, have invented a new and Improved Safety Razor, of which the following is a full, clear, and exact description.

This invention relates to improvements in 10 safety razors, an object of the invention being to provide a safety razor in which the handle forms a continuation of the guard and is located in the same plane with the guard so that the razor may be handled with 15 facility in shaving all parts of the face.

A further object is to provide a novel 20 means for supporting a blade, and to provide a razor which will be simple and practical in construction, comprising a minimum number of parts, yet which will be strong, durable and efficient in use, neat and attractive in appearance, easy to clean, and comparatively inexpensive to manufacture.

With these and other objects in view, the 25 invention consists in certain novel features of construction and combinations and arrangements of parts as will be more fully hereinafter described and pointed out in the claims.

30 In the accompanying drawings:

Figure 1 is a top plan view of my improved razor;

Figure 2 is a view in longitudinal section therethrough on the line 2—2 of Figure 1;

35 Figure 3 is a bottom plan view of the razor;

Figure 4 is a view in transverse section on the line 4—4 of Figure 3; and

40 Figure 5 is a similar view illustrating a modification.

Referring in detail to the drawings, I have used the reference numeral 1 to designate the handle of my improved razor. The handle, it will be noted, is in skeleton form 45 and includes a pair of laterally extending finger receiving portions such as 2. This handle may, if desired, be made solid instead of in the skeleton form shown and may be decorated in any approved manner, as is customary in the art. A guard 3 forms a continuation of the handle, the guard of course being appreciably wider than the handle and being transversely bowed. Relatively narrow guard fingers 4 are provided 50 at the edge of the guard and on the under face of the guard, a pair of longitudinally

extending parallel ribs 5 are integral with the inner ends of the guard fingers. The guard is formed with three openings 6 in its intermediate portion spaced equal distances apart.

Throughout a portion of their length the ribs 5 are formed with opposed grooves such as 7 therein, and a wedge 8 is slidable in the grooves. This wedge is limited in one 65 direction by engagement with the ends of the grooves 7 and in the other direction by a stop 9 fixed to the handle adjacent the guard. The wedge member 8 is formed at its working end with a recess such as 10 70 providing a pair of arms 11. The wedge is likewise formed with a slot 12 adapted to register with one of the openings 6 in the guard and opposite its recessed end is provided with an angular thumb-receiving extension 13 for operating the same.

I have indicated a conventional type of 75 razor blade 14. The blade shown is flexible and is provided with the usual three openings 14' therein. A bowed backing plate 15 80 carries three studs such as 16 which are accommodated in the openings in the blade. The central stud 16 preferably includes a socket 17 and a headed screw 18 in the socket so that this stud may be adjustable 85 and the head movable for the purpose of exerting the desired tension on the blade.

The operation of the device is as follows: The blade 14 is mounted upon the backing plate 15, the studs 16 passing through the 90 openings 14' in the blade. The studs 16 are then passed through the openings 6 in the guard, one of the studs at the same time extending through the slot 12 in the wedge 8. It is merely necessary to slide the wedge 95 forward so that the arms 11 straddle and engage under the head of the screw 18, locking the blade and backing plate in place. The device is then ready for shaving. After use it may be disassembled by merely pulling the wedge member back and allowing the blade and backing plate to fall off. It should be noted that while I have shown the screw 18 in connection with the central stud 16 that I do not wish to be limited to the use 100 of this screw, since a solid stud having grooves therein would serve substantially the same purpose. The screw merely permits a somewhat finer adjustment of tension on the blade.

110 In Figure 5, I have illustrated a modification wherein the wedge 8 is done away with.

In this form of the device, 19 represents the guard, 20 the blade, and 21 the backing plate. Instead of using the wedge member, a central threaded stud or post 22 is provided on the backing plate which passes through the aligned openings in the blade and guard and which receives a clamping nut 23 for locking the parts together and exerting tension on the blade.

10 Although I have illustrated certain of the preferred embodiments of the invention, it will be obvious that various slight changes and alterations might be made in the general form and arrangement of the parts described without departing from the invention, and hence I do not limit myself to the precise details set forth, but shall consider myself at liberty to make such changes and alterations as fairly fall within the spirit 15 and scope of the appended claims.

I claim:

1. A safety razor including a handle, a guard forming a continuation of and located in the plane of the handle and having 25 a guideway in one face thereof, a backing plate, a blade interposed between the guard and backing plate, locking means carried by the backing plate and extending through said blade and guard, and means slidably 30 mounted in the guideway of the guard adapted to engage said locking means for locking all of said parts against relative separation and exerting tension on the blade.

2. In a razor, a guard having openings 35 therein, a blade having openings therein registering with the openings in the guard, a backing plate, studs on the backing plate extending through the registering openings in the guard and blade, one of said studs 40 having a movable head, and a wedge slideable on the guard and engageable with said movable head to lock the parts against relative separation.

3. In a razor, a guard having openings 45 therein and having a guideway in one face thereof, a blade having openings therein registering with the openings in the guard, a backing plate, studs on the backing plate extending through the registering openings

in the guard and blade, a wedge slideable in 50 the guideway of the guard and engageable with one stud to lock the parts against relative separation, said stud including a movable head, and said wedge including a pair of beveled arms straddling the stud and engaging under the movable head. 55

4. In a razor, a guard having openings therein, a blade having openings therein registering with the openings in the guard, a backing plate, studs on the backing plate 60 extending through the registering openings in the guard and blade, a wedge slideable on the guard and engageable with one stud to lock the parts against relative separation, said stud including a movable head, said 65 wedge including a pair of beveled arms straddling the stud and engaging under the head, and said wedge including an angular extension at one end constituting a finger piece for sliding the wedge. 70

5. In a razor, a guard having openings therein, a blade having openings therein registering with the openings in the guard, a backing plate, studs on the backing plate 75 extending through the registering openings in the guard and blade, a wedge slideable on the guard and engageable with one stud to lock the parts against relative separation, said stud including a head, said wedge including a pair of beveled arms straddling 80 the stud and engaging under the head, and grooved ribs in said guard providing sliding mounting for said wedge.

6. In a razor, a guard having openings therein, a blade having openings therein 85 registering with the openings in the guard, a backing plate, a series of studs on the backing plate extending through the registering openings in the guard and blade, a wedge slideable on the guard and engageable with 90 one stud to lock the parts against relative separation, said stud including a movable head, said wedge including a pair of beveled arms straddling the stud and engaging 95 said movable head, and grooved ribs on said guard providing a sliding mounting for said wedge.

MACE LOWRANCE MASTERS.
